Primary Examiner — Nicole C Shiflet*(74) Attorney, Agent, or Firm* — MINTZ LEVIN COHN FERRIS GLOVSKY AND POPEO, PC(57) **CLAIM**

We claim the ornamental design for a handle for cookware, as shown and described.

DESCRIPTION

FIG. 1 is an isometric view of the handle for cookware;
FIG. 2 is a front view of the handle for cookware;
FIG. 3 is a rear view of the handle for cookware;
FIG. 4 is a side view of the handle for cookware;
FIG. 5 is another side view of the handle for cookware;
FIG. 6 is a top view of the handle for cookware; and,
FIG. 7 is a bottom view of the handle for cookware.
The broken lines illustrate environment and features of the handle for cookware that form no part of the claimed design.
Claimed subject matter is shown with shading.

1 Claim, 7 Drawing Sheets(56)
